HOLDER FOR DETERGENT

George Buckham Reilly, Chapeltown, near Sheffield, Edward Jollasse Miles, Sheffield, Tom Bennett Lewis, Moreton, and Francis George Melsher, Liverpool, England, assignors to Newton, Chambers & Company Limited

Filed July 13, 1959, Ser. No. 826,630

Claims priority, application Great Britain July 16, 1958

7 Claims. (Cl. 45—28)

This invention relates to holders for detergents.

The common ways of introducing a detergent into a bowl of water for household purposes, and particularly for washing up, are to pour it into the bowl in liquid form or to add it to the water as powder. It has previously been appreciated that it would be advantageous to provide a solid annular block of detergent around a stick, and to immerse the block while holding the stick so as to dissolve some of the block in the water.

The object of this invention is to provide an improved holder for such a solid block of detergent.

Broadly stated, in our invention a holder for a block of detergent with a central hole comprises a cage for the block and a rod extending through the cage from one end to the other to pass through the central hole in the block and to extend outwards as a handle. The cage is made in two parts separable to allow a block to be put around the rod.

In use the cage containing a block is immersed in water and used as a stirrer so that some of the block is dissolved. It is desirable that the block should fit loosely around the rod so that it will move within the cage during this stirring operation and the water will have access to the surface of the central hole in it as well as to its outer surface.

The holder is advantageously as light as possible, and the rod serves to strengthen a light construction, to prevent the block from damaging the wall of the cage during the shaking and to form the handle by which the holder is held.

Some holders according to this invention will now be described by way of example with reference to the annexed drawings, in which:

Figure 1 is a perspective view of the preferred holder with a block of detergent in it;

Figure 2 is an axial section through the same holder with the block removed;

Figure 3 is an axial section through a modification of the holder; and

Figure 4 is an axial section through another holder.

The holder shown in Figures 1 and 2 comprises a rod 1 moulded from polystyrene and a cage 2 moulded from polythene, the cage housing a block 3 of detergent made in one piece with a central hole. The cage comprises two identical basket-like parts 4, each having a solid base 5 with an open central socket 18, an upper rim 6 and ribs 7 joining the base to the rim to form openwork sides. Part-spherical bosses 8 are moulded to project from the bases 5 so that the holder rests on the bosses when it is stood upright on a level surface.

The rod 1 is a unit separate from the cage and comprises a fluted handle part 9 having a hole 10 at one end so that it can be hung up. The part of the rod within the cage passes through the hole in the middle of the block 3. Flutes 13 forming a cruciform section are formed on the surface of this part of the rod so as to increase the abrasive action between the block and the rod when the holder is shaken in water, and so as to

2

allow the water better access to the walls of the hole. A flange 14 is formed at the bottom of the rod and two small studs 12 project from the surface of the flutes 13 at a short distance from the flange to engage the rim 5 of the bottom socket 18. The flutes 13 are made slightly deeper at each end at 15 so as to grip the inner walls of the sockets 18. When the holder is assembled, the socket 18 of the bottom part 4 makes a force fit over the flutes, axial movement of the part 4 along the rod being resisted by the flange 14 and studs 12. The rims 6 of the two cups lie flush one against the other and the socket 18 of the top part 4 makes a force fit over the flutes 15.

The holder will normally be kept in an upright position on, say, a draining board, and will rest on the end of the cage remote from the handle. This part of the cage may advantageously have an upturned rim as shown at 11 to hold the concentrated solution of detergent which is likely to form by drainage.

The fact that the basket-like parts 4 are identical facilitates manufacture. However, two parts differing in construction may be used, one example being shown in Figure 3. Here the shaft 19 is secured to a bottom basket part 20 in the manner already described. The bottom part 20 now constitutes an openwork bucket for a block of detergent not shown, and the top part 21 a lid for the bucket. The part 21 has a central hole enabling it to slide freely over the shaft 19, and has a downward-projecting cylindrical outer skirt 22. This skirt is formed with a groove 23, which receives a raised edge 24 projecting outwards from the upper rim 25 of the part 20 and so secures the two parts together.

In the holder of Figure 4 two parts 26 and 27 are shown similar to those seen in Figures 1 and 2, but the bottom part 26 is moulded in one piece with the rod 28, and both parts have tabs 29 projecting from the inward edges of the rim 30. The tips of the tabs of one part fit within, and round the rim of, the other when the holder is assembled, and thus help to key the two parts together. The base of the part 26 is perforated by holes 31 through which liquid can drain from the holder when the latter is stood upright on the base.

Other modifications may be made. For instance, the rod may be composite, the handle part being detachably secured to the part that passes through the block.

The block shown is made in one piece and so must be pushed over the rod, but it can be divided axially and the two parts can be held together in any convenient way, e.g. by an elastic band, so that together they form a block.

We claim:

1. A holder for a block of detergent, having a hole through the middle, said holder comprising a cage for the block and a rod extending through the cage from one end to the other to pass through the hole in the block, making contact with each end of the cage and extending outwards as a handle, the cage being made in two parts separable to allow the block to be put round the rod.

2. A holder according to claim 1 in which the end of the rod enters a socket in the part of the cage remote from the handle.

3. A holder according to claim 1 in which the part of the cage nearer the handle makes a force fit with the rod.

4. A holder according to claim 1 in which projections are formed on the rod where the block fits over it, so as to increase the abrasive action between the block and the rod.

5. A holder according to claim 1 in which bosses are formed on the bottom of the cage.

6. A holder for a block of detergent, having a hole through the middle comprising two identical cage parts, each having a base with a central socket and openwork

sides, and a rod passing through the hole in the block and engaging both sockets and extending outwards at one end to form a handle.

7. A holder according to claim 6 in which the end of the rod passes through the socket in the part of the cage 5 remote from the handle and has a flange engaging the outer surface of this cage part.
